UNITED STATES PATENT OFFICE

MARSHALL A. RUSSOW, OF CHICAGO, ILLINOIS

IRRIGATOR

Application filed October 3, 1928. Serial No. 310,133.

The present invention is directed to improvements in irrigators.

The primary object of the invention is to provide a device of this character so constructed that the same can be conveniently suspended upon a wall or placed upon a support, the construction being such that the vessel and discharge hose connected thereto will be completely concealed from view.

10 Another object of the invention is to provide a device of this kind constructed in such manner that the vessel can be removed from the holder in order that the same can be thoroughly sterilized.

15 Another object of the invention is to provide a device of this kind wherein the position of the discharge hose controls the flow of liquid from the vessel.

Another object of the invention is to provide a device of this kind which is extremely simple in construction, efficient in operation, durable, and one which can be manufactured at a very small cost.

With these and other objects in view, this 25 invention resides in the novel features of construction, formation, combination and arrangement of parts to be hereinafter more fully described, claimed and illustrated in the accompanying drawings, in which:—

30 Figure 1 is a perspective view of the device.

Figure 2 is a sectional view on line 2—2 of Figure 1.

Figure 3 is a sectional view on line 3—3 of 35 Figure 1.

Figure 4 is a bottom plan view.

Figure 5 is a detail sectional view through the discharge pipe.

40 Figure 6 is a sectional view on line 6—6 of Figure 5.

Referring to the drawings, 1 designates a holder preferably formed from sheet metal, said holder comprising a back 2, sides 3, and a bottom 4. The forward edges of the sides 3 are turned to provide flanges 5 to produce grooves 6, the purpose of which will be later explained. The back 2 is provided with a plurality of perforations 7 for the passage 50 of securing devices in order that the holder

can be conveniently secured to a wall or other support.

The upper edges of the sides are provided with beveled or sloping portions 8 in order that the closure to be hereinafter described 55 can more readily operate.

A vessel 9 is employed and is capable of being removably mounted in the holder 1, said vessel being formed from glass, porcelain or any other suitable material. This vessel includes a back wall 10, side walls 11, a front wall 12, and a bottom 13.

The forward edges of the sides 11 extend beyond the front wall 12 and constitute ribs 14 adapted to engage in the grooves 6 when 60 the vessel is engaged in the holder.

It will be observed upon reference to Figure 3 that the front wall 12 is of less height than the side walls 11, the purpose of which 65 will later appear.

The front wall 12 of the vessel 9 is provided near its lower end with an opening 15 in which is threaded the inner end of the pipe 16, said pipe having an annular shoulder 17 thereon and against which the inner end of the sleeve 18 bears, said sleeve being rotatably mounted upon the pipe 16 and has carried thereby a nipple 19.

The sleeve is retained upon the pipe by a cap screw 20 which threads in the outer ends 80 of the pipe 16, as clearly shown in Figure 5 of the drawings.

A rubber hose 21 is provided and has one end secured to the nipple while the other end carries a nozzle 21'.

85 The pipe 16 is provided with a discharge opening 22 adapted to register with the bore of the nipple 19 when said nipple is swung downwardly to permit the contents of the vessel to flow into the hose 21. It will be of course understood that when the nipple is swung upwardly the sleeve 18 will close the opening 22 to prevent liquid from entering the hose.

To the bottom 4 of the holder is secured a pair of clips 23 in which is supported the pintle 24. A closure 25 is provided and has its bottom 26 provided with sleeves 27 for pivotally engaging the pintle 24 in order that 90 95 100

the closure can be swung to its open or closed position.

This closure includes side walls 24', a top wall 22 and a front wall 29 which envelopes the holder when the closure is in its closed position.

When the closure is in its closed position the wall 29 thereof is spaced from the wall 12 of the vessel in order that space is provided to accommodate the hose 21 as clearly shown in Figure 3, and at which time the hose is sustained in its inoperative position by turning the same upon the upper edge of the wall 12.

When it is desired to use the device the closure is swung open and the hose is removed from the wall 12 in order that the sleeve 18 can rotate to swing the nipple 19 downwardly to bring the bore thereof in registration with the opening 22. The flow of liquid from the vessel can be stopped or regulated at any time by swinging the nipple to its closed or partially closed position.

When the device is not in use the closure will prevent the entrance of dust or other foreign matter into the vessel and will maintain the same in a thoroughly sanitary condition which is extremely desirable in articles of this character.

The rear wall 10 of the vessel is provided with perforations 30 for the passage of a securing device to suspend the same should it be desired to use the vessel when removed from the holder.

The vessel may be provided with any suitable graduations or other indicating means in order that the solutions can be properly mixed.

From the foregoing, it is thought that the construction, operation and many advantages of the herein described invention will be apparent to those skilled in the art, without further description, and it will be understood that various changes in the size, shape and proportion, and minor details of construction may be resorted to without departing from the spirit or sacrificing any of the advantages of the invention.

If desired a catch 31 may be employed for positively holding the closure in its closed position.

Having thus described the invention, I claim:

1. A surgical irrigator comprising a vessel, a fluid discharge pipe connected with the vessel, a closure sleeve rotatably mounted on the pipe, a hose connected with the sleeve and supported by the vessel to normally hold the closure sleeve against rotation to prevent the flow of fluid from the vessel into the hose and to permit flow of fluid when the hose is disengaged from the vessel

2. As a new article of manufacture, an irrigator comprising a vessel having a discharge pipe connected therewith, a sleeve rotatable on the pipe and having a nipple, a discharge

hose connected to the nipple and rotatable to rotate the sleeve to control the flow of fluid from the vessel into the hose.

3. A surgical irrigator comprising a holder having an open side and adjacent grooves, a vessel having laterally spaced vertically extending ribs reliabely engaged in the grooves, a closure normally confining the holder and vessel, said ribs maintaining the front walls of the vessel and closure normally spaced, and a hose connected with the vessel and confined within the space defined by the ribs and respective front walls.

In testimony whereof I affix my signature.
